Primary Examiner — Phillip S Hyder(57) **CLAIM**

The ornamental design for a slotted screwdriver blade tip, as shown and described.

DESCRIPTION

This patent application may be related to one or more of the following patents and/or patent pending applications granted to the inventor herein: U.S. D583,642 S.

FIG. 1 is a perspective view of a slotted screwdriver blade tip top showing my new design;

FIG. 2 is a front elevation view thereof;

FIG. 3 is a right side elevation view thereof; and,

FIG. 4 is a bottom plan view thereof.

The rear elevation view is a mirror image of the front elevation view as shown.

The left side elevation view is a mirror image of the right side elevation view as shown.

The top of the slotted screwdriver blade tip forms no part of the claimed design.

The broken line disclosure in FIGS. 1-4 define the boundary of the claimed subject matter, but form no part of it.

1 Claim, 1 Drawing Sheet(56)
